UNITED STATES PATENT OFFICE.

SAMUEL B. KULL, OF NEW YORK, N. Y.

RAIL-FASTENING.

1,049,876.

Specification of Letters Patent.

Patented Jan. 7, 1913.

Application filed April 13, 1911. Serial No. 620,720. Renewed June 8, 1912. Serial No. 702,620.

To all whom it may concern:

Be it known that I, SAMUEL B. KULL, a citizen of the United States, and a resident of the city of New York, borough of Manhattan, in the county and State of New York, have invented a new and Improved Rail-Fastening, of which the following is a full, clear, and exact description.

The object of the invention is to provide 10 a new and improved rail fastening, arranged to securely hold the rail in place and to prevent spreading of the same.

For the purpose mentioned, use is made 15 of converging spikes, of which one is the rail spike and engages the rail and the other is the locking spike and engages the rail spike to lock the latter against displacement.

A practical embodiment of the invention is represented in the accompanying drawings forming a part of this specification, in 20 which similar characters of reference indicate corresponding parts in all the views.

Figure 1 is a plan view of the improved rail fastening as applied for fastening two 25 rails to a tie; Fig. 2 is an enlarged sectional elevation of the same on the line 2—2 of Fig. 1; Fig. 3 is a plan view of part of the tie; Fig. 4 is a perspective view of the rail spike; Fig. 5 is a similar view of the locking spike; Fig. 6 is a sectional side elevation of 30 a modified form of the fastening; and Fig. 7 is a cross section of the same.

On top of the tie A are arranged the plates or chairs B for the rails C to rest on, and 35 each of the said plates B is provided with two pairs of depending and converging pockets or guideways B', B'', of which the pocket B' contains a rail spike D having a head D' engaging the base of the rail C, 40 and the other pocket B'' contains a locking spike E having a head E' and an undercut E'' to permit of bending the head E' over onto the head D' of the rail spike D, to hold the latter against outward movement in its 45 pocket B'.

By the arrangement described, the spikes D and E stand obliquely one to the other, with their heads D' and E' in engagement as described, so that one spike locks the other 50 against outward movement in the corresponding pockets B', B'', as will be readily understood by reference to Fig. 2. The railroad tie A is preferably formed of a body A', of wood, having transverse recesses A'' 55 for the reception of the pockets B', B'', as plainly indicated in Figs. 2 and 3, and the

said body A' is covered with a coating A² of asphalt, or a similar waterproofing material, and the coating A² is covered by sheet metal A³ to protect the coating A² from 60 being knocked off the body A' especially when handling, laying or re-laying the ties on the road bed.

It is understood that a pair of spikes D and E is used on each side of the rail C on 65 each of the plates B, so that the rail is securely locked in position and is held against displacement and spreading.

It is understood that in placing the spikes D and E in place, the spike D is first driven 70 into position in its pocket B' until the head D' engages the base of the rail C, and then the spike E is driven into the pocket B'' and its head E' is bent over onto the head D', so that the corner of the head D' is engaged by 75 the undercut E'' and the head E' to securely lock both spikes D and E against outward movement.

In the modified form shown in Figs. 6 and 7, the plate B³ is provided with single 80 pockets B⁴ and B⁵ on opposite sides of the rail C, and the said pockets are diverging and each is adapted to receive a spike F having a head F' engaging the base of the rail C. From each head F' extends upwardly a locking arm F² adapted to be bent 85 inward under the head of the rail C after the spike F is in place, as will be readily understood by reference to Fig. 7. By the arrangement described the spike F is held 90 against outward movement in the corresponding pocket B⁴ or B⁵ by the action of the arm F² and at the same time the arm F² forms a brace for the rail C, to hold the same 95 against spreading.

Having thus described my invention, I claim as new and desire to secure by Letters Patent:—

1. A rail fastening, comprising a plate for the rail to rest on and having depending 100 angular pockets, rail spikes, and locking spikes engaging the pockets, the locking spikes having heads adapted to engage the heads of the rail spikes.

2. A rail fastening, comprising a plate for the rail to rest on and provided with a pair of oblique pockets, a rail spike engaging one of the pockets and having a head adapted to engage the rail, and a locking spike engaging the other pocket and having a head engaging the head of the rail spike.

3. A rail fastening, comprising a plate for

the rail to rest on and provided with a pair of depending and converging pockets, a rail spike engaging one of said pockets and having a head adapted to engage the base of the rail, and a locking spike engaging the other pocket and having a head and an undercut adjacent to the head, the said spikes standing obliquely one to the other, and the head and undercut of the locking spike being adapted to engage the corner of the head of

the rail spike to lock the spikes against outward movement.

In testimony whereof I have signed my name to this specification in the presence of two subscribing witnesses.

SAMUEL B. KULL.
